Primary Examiner — Caron D Veynar*Assistant Examiner* — Abraham Bahta**CLAIM**

The ornamental design for a flexible pouch, as shown and described.

DESCRIPTION

FIG. 1 is a front elevational view of a flexible pouch, showing the design of the pouch when unfilled. The rear elevational view of the flexible pouch when unfilled is a mirror image of this view.

FIG. 2 is a side elevational view of the flexible pouch, showing the design of the pouch of FIG. 1 when filled. The opposite side elevational view is a mirror image of this view.

FIG. 3 is a bottom plan view of the flexible pouch, showing the design of the pouch of FIG. 1 when filled; and,

FIG. 4 is a front elevational view of the flexible pouch, showing the design of the pouch when filled. The rear elevational view of the flexible pouch when filled is a mirror image of this view.
